UNITED STATES PATENT OFFICE

HERMAN J. HAMMERLY, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT

ELECTRIC SWITCH

Application filed June 11, 1932. Serial No. 616,605.

My invention relates particularly to enclosed switches and the construction and arrangement of the contacting parts and insulation and means for supporting the conducting parts.

One object is to provide a compact, simple and inexpensive type of construction.

Another object is to provide a construction of the foregoing character which is durable and reliable in operation.

Another object is to provide a construction in which there is no liability of the movable switch member sticking or failing to operate properly.

Another object is to provide a switch construction which is readily adapted for quick-make and quick-break action and in which the correlated parts are so arranged as to permit the switch unit to be made considerably shorter and more compact than in former similar constructions.

In its preferred form the invention contemplates the use of an insulating base with the stationary contacts housed within passages which also guide the movable switch members. Each movable switch member consists of a flat plate of insulating material having a perforation in which is loosely mounted a conducting roller. This base is suitably supported by a carrier which also supports the operating crank shaft and snap action mechanism for operating the switch.

Fig. 1 is a front view of a construction embodying my invention as applied to a two pole switch, the stationary contacts and terminals of one of the poles being removed to show the interior construction of the base.

Fig. 2 is a vertical sectional view and end elevation, the parts of the switch being shown in the off or open circuit position.

Fig. 3 is a longitudinal sectional view showing the parts of the switch in the on or closed circuit position.

Fig. 4 is a side view and section showing one set of stationary contacts, together with the movable switch member and operating crank, the parts being in the open circuit or off position.

Fig. 5 is an exploded perspective view

showing the movable and stationary elements of one pole of the switch.

The main body or insulating base 7 may be formed of any suitable material for the purpose of supporting the conducting members of the switch.

Each switch unit has stationary contacts 8 and 9 of suitable material preferably in the form of bowed springs spaced apart from each other and adapted to receive between them a roller 10 which may be either solid or tubular. The upper contact 8 is provided with a circuit terminal foot or extension 11 secured to the base by a screw 12, and the lower contact 9 has a similar foot 13 secured to the base by a screw 14.

The form shown is adapted to employ protective fuses of the cartridge type (not shown) and for this purpose fuse clips 15 and 16 are provided. The clip 15 is secured to the foot of the contact 9 and to the base by a screw 17 and the clip 16 is secured to the circuit terminal 18 by means of a screw 19.

The contacts 8 and 9 are located or housed in recesses such as 20 and 21 and the movable switch member 10 is carried by a flat plate 22 of insulating material having an aperture 23 in which the roller 10 is loosely supported. This plate 22 has its edges guided in grooves 24 between the upper and lower contacts.

In the closed circuit position the contact roller 10 is tightly gripped between the spring-like upper and lower contacts 8 and 9 but when the switch is off the projections 22' on the outer end of the insulating plate 22 are positioned between the outer ends of the contact members 8 and 9 as shown in Fig. 4, and thus hold the plate in position and prevent the parts from rattling. The contact roller 10 is guided to a certain extent between the shoulders 25, 25 between the recesses 20 and the grooves 24. In the open circuit position the contact roller is positioned between the shoulders 26, 26 at the bottoms of the recesses 20 and 21. The ends of the spring contacts 8 and 9 are curved or inclined away from the contact carrier 22 so as to facilitate the operation of the switch toward the closed circuit position and also so that the spring action will tend to throw the contact roller

toward the open circuit position as the contact roller leaves the ends of the inclined tips 27.

The insulating base is provided with pedestals or feet 28 and 29 which are supported on the back plate 30, for instance, by screws 31 and 32. This back plate has a side flange 33, which two parts serve as a mounting or carrier for the switch contacts and operating mechanism so that the entire switch and its operating mechanism may be handled as a unit.

The crank shaft 34 has its opposite ends pivotally supported in the bracket 35 and in the hub 36. This crank shaft is connected to the plates or slides which carry the movable contacts. This connection may, for instance, be effected by means of a metallic open U-shaped lug 37 which may be riveted or otherwise suitably secured to the plate 22.

By removing the screws 31 and 32 the switch block and the contact and terminal members may be readily removed from the carrier by simply moving the base upwardly sufficient to disengage the U-shaped lug 37 from the crank shaft 34. Obviously the parts may be readily assembled in the reverse order.

The back plate 30 serves as an abutment to the contact carrying plates 22 when they are moved to the open circuit position, and the flange 38 of the bracket 35 serves as an abutment for the crank shaft 34 when the contacts 10 of the switch are moved to the closed circuit position.

It should be understood that the back plate 30 and the side flange 33 are merely illustrated as a typical method of installing the switch mechanism in a box in the customary manner. This same carrier supports the operating handle 39 which is connected to the hub 36. The disc 40 is supported on the hub 36 with a lost motion connection of the usual character and is connected to the rod 41 which carries the spring 42 and slides in the abutment plate 43 in the usual way. This disc 40 has lugs 44 and 45 spaced apart from each other and adapted to engage one arm of the crank shaft 34, also in the usual manner.

The operation of the snap action mechanism readily adapts itself to the combination with the switch herein shown and described. It should be understood, however, that the invention claimed herein primarily resides in the construction of the stationary contacts and the movable roller contacts and the method of supporting and housing the contacts. The insulating slide or plate 22 being flat and merely provided with a perforation or aperture for the contact roller 10 is not only very cheap to manufacture and assemble but produces a compact construction which requires a supporting base of minimum size and maximum simplicity of construction, and which can be readily molded out of insulat-

ing material at a minimum of expense. The contact rollers being loosely mounted in the insulating plates have great freedom of action and consequently readily adapt themselves to the associated stationary contacts and thus provide adequate and reliable electrical engagement even though the spring contacts may be somewhat irregular in form or inaccurately located. These contact rollers are also continually changing their position as the switch is actuated, as a consequence of which the rollers are continually presenting new surfaces to the stationary contacts, thus avoiding any difficulties which might be produced by pitting of the stationary or movable contacts.

The contact rollers being supported in the insulating plates and guided in the insulating base, there is very little opportunity for arc²³ing and, furthermore, any arc which does tend to form is confined to the base and can not escape outwardly to cause any fire hazard. The insulating plate and the passage in the base in which it is guided are arranged transversely with respect to the base which makes it possible to provide a mounting means for the roller contact of the cheapest possible form and also makes it possible to mount the stationary contacts 8 and 9 comparatively very close together, thus permitting the base to be made considerably shorter and more compact than former similar switch constructions. The shortening of the base makes it possible to shorten the enclosing box an equal amount or the additional space provided in a box of the same length may be utilized as additional wiring space.

I claim:

1. In an electric switch, an insulating base having a transversely extending passage from front to rear with a recess at each side of the passage, a spring contact mounted in each of said recesses, a flat plate guided in the base between said recesses and a roller loosely supported in said plate between said spring contacts.

2. In an electric switch, an insulating base having a transversely extending passage therethrough from front to rear with a recess at each side of the passage, a contact mounted in each of said recesses, a flat plate guided in the passage in the base between said recesses and a roller loosely supported in said plate between said spring contacts and guided between walls of said passage.

3. In an electric switch, an insulating base having a transversely extending passage therethrough from front to rear with a recess above and a recess below the passage, a contact mounted in each of said recesses, a flat plate guided in the base between said recesses and a roller loosely supported in said plate between said spring contacts, said plate having projecting means for holding the plate in position between the contacts.

4. In an electric switch, an insulating base having a passage transversely extending therethrough from front to rear, spring contacts mounted on opposite sides of said passage, guide grooves in opposite sides of said passage, a flat insulating plate guided in said grooves and having a perforation and a contact roller loosely supported in said perforation and of greater diameter than the thickness of said plate, said passage having shoulders serving as confining guides for the ends of the contact roller. 70
5. In an electric switch, an insulating base having a passage extending therethrough from front to rear with a recess at each of the opposite sides of said passage, a contact mounted in each of the recesses, guide grooves in opposite sides of said passage, a flat insulating plate guided in said grooves and having a perforation and a contact roller loosely supported in said perforation and of greater diameter than the thickness of said plate for engaging said contacts, said passage having shoulders serving as confining guides for the ends of the contact roller when in its open circuit position. 75
6. In an electric switch, an insulating base having a transversely extending passage therethrough from front to rear, spring contacts mounted on opposite sides of the said passage, guide grooves in opposite sides of said passage, a flat insulating plate guided in said grooves and having a perforation and a contact roller loosely supported in said perforation and of greater diameter than the thickness of said plate, said contacts having outwardly inclined tips for engaging said roller to hasten the breaking of the circuit. 80
7. An electric switch including a supporting back plate, a bracket secured to one edge of the plate and a side plate secured to the opposite edge, an insulating base supported by the back plate, an operating crank shaft pivotally supported by said bracket and said side plate beneath said base, contacts carried by said base, a flat insulating plate guided to reciprocate through said base between said contacts, a roller loosely carried by said insulating plate between said contacts, said back plate serving as a rear abutment for said insulating plate. 85
8. An electric switch including a supporting back plate, a bracket secured to one edge of the plate and a side plate secured to the opposite edge, an insulating base supported by the back plate, an operating crank shaft pivotally supported by said bracket and said side plate beneath said base, contacts carried by said base, a flat insulating plate connected to said crank and guided to reciprocate through said base between said contacts and a roller loosely carried by said insulating plate between said contacts, said bracket having a flange serving as an abutment for said crank. 90
9. An electric switch including a supporting back plate, a bracket secured to one edge of the plate and a side plate integral with the opposite edge, an insulating base supported by the back plate and having a transversely extending passage with guide shoulders, a crank shaft pivotally supported by said bracket and said side plate beneath said base, contacts carried by said base at opposite sides of said passage, a flat insulating plate guided to reciprocate in said passage between said contacts, and a roller loosely carried by said insulating plate between said contacts and guided between said shoulders. 95
10. An electric switch including a supporting back plate, a bracket secured to one edge of the plate and a side plate integral with the opposite edge, an insulating base supported by the back plate, a crank pivotally supported by said bracket and said side plate beneath said base contacts carried by said base, a flat insulating plate connected to said crank and guided to reciprocate through said base between said contacts, a roller loosely carried by said insulating plate between said contacts, said back plate serving as a rear abutment for said insulating plate and said bracket having a flange serving as a stop for said crank. 100
